UNITED STATES PATENT OFFICE.

CLARENCE J. LUTHER, OF MILWAUKEE, WISCONSIN, ASSIGNOR TO LUTHER GRINDER MANUFACTURING COMPANY, OF MILWAUKEE, WISCONSIN, A CORPORATION OF WISCONSIN.

HONING IMPLEMENT FOR CHISELS, &c.

1,132,663.

Specification of Letters Patent. Patented Mar. 23, 1915.

Application filed August 1, 1913. Serial No. 782,406.

To all whom it may concern:

Be it known that I, CLARENCE J. LUTHER, a citizen of the United States, residing at Milwaukee, county of Milwaukee, and State 5 of Wisconsin, have invented new and useful Improvements in Honing Implements for Chisels, &c., of which the following is a specification.

My invention relates to improvements in 10 honing implements for chisels, etc.

The object of my invention is to provide a form of tool adapted to not only facilitate the desired movement of the tool over the stone, but which will also hold the tool at 15 the proper angle for properly honing the beveled edge, and will allow for and facilitate swinging movements where a curved edge is to be ground or honed, and prevent swinging movements where a straight edge 20 is to be ground or honed.

In the drawings,—Figure 1 is a plan view of an implement embodying my invention, showing a portion of a tool in position for honing. Fig. 2 is a vertical sectional view 25 drawn to a plane cutting the tool longitudinally. Fig. 3 is a detail rear view of the tool holder.

Like parts are identified by the same reference characters throughout the several 30 views.

A stone holder 1 is adapted to receive and retain a stone 2. The holder is provided with raised side walls 3. A tool holder is mounted upon a rod 4, which is adapted to 35 span the stone holder transversely and to slide freely upon the upper margins of the side walls 3. A bar 6, preferably parallel to the rod 4, is supported above said rod by posts 7, and an arm 8, rigidly connected 40 with the rod, carries a rotating disk 10 centrally pivoted to the arm 8 and serving as a tool rest. A clamping screw 12 has threaded bearing in the bar 6 and has a pointed lower end adapted to bear upon the 45 tool blade above the disk 10 and preferably perpendicular to its center of rotation. A pair of arms 14 extend downwardly from, and diagonally to the front and rear of the bar 6, and are longitudinally adjustable 50 thereon, being connected with the bar by a slotted connecting member 16 and a pair of set screws 17, which pass through the slots and are engaged in threaded apertures or sockets in the bar. The set screws hold the

arms 14 in planes at right angles to the axes 55 of the bar 6 and rod 4.

A tool, such as the blade 18 of a chisel, is applied to the disk or tool rest 10, and the set screw 12 turned to clamping position, the tool blade being first adjusted longitudinally over the rest 10 to secure the proper bevel, and being also adjusted laterally to a point where the set screw will bear upon it in a longitudinal central plane. If it is desired to prevent the blade from oscillating, 65 the bracket (comprising member 16 and arms 14) is adjusted with the arms 14 in contact with the side of the tool blade. But if the edge of the tool is rounded, the bracket arms may be moved away from the tool and 70 secured at a point where they will limit the oscillations of the tool and tool rest in conformity to the desired curve of the cutting edge. When the tool has been thus adjusted and secured in position, it or its handle, may 75 be grasped and the tool moved in a circular path, the rod 4 sliding upon the raised margins of the stone holder. It is obvious that at all stages of this movement the angle of the tool with reference to the stone will be 80 maintained, and the tool may therefore be ground true and to a uniform bevel. The posts 7 which support the bar 6 are preferably so located that only one of them will be between the raised side walls 3, so that 85 these posts will not interfere with the freedom of movement of the rod upon said walls.

I claim,—

1. A honing implement, comprising a 90 stone holder having raised side margins, a rod adapted to span the holder and to slide freely in all directions upon the margins, a tool rest carried by the rod, and a clamping device supported from the rod in clamping 95 relation to the tool holder.

2. A honing implement, comprising a stone holder having raised side margins, a rod adapted to span the holder and to slide 100 freely in all directions upon the margins, a tool rest carried by the rod, and a clamping device supported from the rod in clamping relation to the tool holder, said tool rest being centrally pivoted to its support and adapted to oscillate with the tool when the 105 tool is moved with a honing motion over the face of the stone.

3. A honing implement, comprising a

- stone holder having raised side margins, a rod adapted to span the holder and to slide freely upon the margins, a tool rest carried by the rod, and a clamping device supported from the rod in clamping relation to the tool holder, said tool rest being centrally pivoted to its support and adapted to oscillate with the tool when the tool is moved with a honing motion over the face of the stone, together with a bracket adjustably supported from said rod and adapted to be secured in position to prevent such oscillations of the tool.
4. In a honing implement, the combination with a supporting rod free to move in all directions of a tool rest rotatably supported therefrom, and a clamping device adapted to engage a tool between it and the tool rest.
- 20 5. In a honing implement, the combination with a supporting rod of a tool rest
- rotatably supported therefrom, and a clamping device adapted to engage a tool between it and the tool rest, together with an adjustable bracket, having arms adapted to bear against the sides of such engaged tool.
6. In a honing implement, the combination of a tool rest, a supporting rod for the tool rest, a bar supported from the rod in a position parallel thereto, and a clamping set screw supported from said bar, said bar and rod being separated sufficiently to permit the tools to pass between them into contact with the tool rest.

In testimony whereof I affix my signature in the presence of two witnesses.

CLARENCE J. LUTHER.
